Specification for Design.

Patented Feb. 2, 1915.

Application filed October 17, 1914. Serial No. 867,250. Term of patent 14 years.

To all whom it may concern:

Be it known that I, CHARLES L. SULLIVAN, a citizen of the United States, and residing at Moundsville, in the county of Marshall and State of West Virginia, have invented a certain new, original, and ornamental Design for a Glass Vessel or Similar Article, of which the following is a specification, reference being had to the accompanying drawings, forming a part thereof, wherein—

Figure 1 is a perspective view of a drinking glass showing an application of the new

design, and Fig. 2 is a side elevation of the same.

The design is shown applied to a tumbler of conventional form, the shape of which is not claimed.

I claim:—

The ornamental design for a glass vessel or similar article, substantially as shown.

CHARLES L. SULLIVAN.
